(57) **CLAIM**

The ornamental design for a flat panel speaker, as shown and described.

DESCRIPTION

FIG. 1 is a top, rear, left perspective view of a flat panel speaker, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof, shown in an enlarged scale; and,

FIG. 7 is a bottom plan view thereof, shown in an enlarged scale.

Dotted lines shown in the drawings represent environmental subject matter and form no part of the claimed design.
